GLAZING AND POLISHING MACHINE

William C. Burt, Olean, N. Y., assignor to Clair
Manufacturing Company, Inc., Olean, N. Y.

Application March 1, 1950, Serial No. 147,053

8 Claims. (Cl. 51—85)

1

This invention relates to improvements in surface finishing machines of the type known as glazing and polishing machines, and more particularly to machines for glazing and polishing multiple lots of cutlery articles, tools, hardware, and the like. Furthermore, the present invention relates to improvements in the general type of machines disclosed in United States Patents Nos. 2,188,223, 2,269,311, and 2,458,708, and embodies improvements in the art thereover whereby such machines may be more versatile and more fully automatic in their operation.

One of the objects of the present invention is to provide an improved machine for polishing and glazing articles, as aforesaid. Another object of the invention is to provide in a machine for the purposes aforesaid, improved automatic means for stopping and opening the machine subsequent to a preselected time cycle of operation, for unloading and reloading of the machine. Another object of the invention is to provide an improved machine for the purposes aforesaid, embodying improved work piece mount positioning and stroke control relative to the glazing or polishing rolls whereby the work pieces are fed to the polishing or glazing rolls in improved manner. Another object of the invention is to provide an improved machine for the purposes aforesaid, embodying improved work piece movement control features, whereby the workpieces are automatically motivated relative to the machine rolls during each operative cycle in improved manner. Other objects and advantages of the invention will appear in the specification hereinafter.

In the drawings:

Fig. 1 is a fragmentary top plan view of the front end portion of a polishing or glazing machine constructed in accordance with the invention;

Fig. 2 is a front elevational view thereof;

Fig. 3 is a fragmentary end view with portions shown in section taken along line III—III of Fig. 2;

Fig. 4 is a fragmentary sectional detail taken along line IV—IV of Fig. 2;

Fig. 5 is a fragmentary section taken along line V—V of Fig. 2;

Fig. 6 is a fragmentary section taken along line VI—VI of Fig. 1;

Fig. 7 is a schematic diagram of a portion of the pneumatic-hydraulic automatic cycling and workpiece feeding reciprocation control mechanism of the machine;

Fig. 8 is a diagram of a portion of the hydraulic workpiece oscillation control mechanism; and

Fig. 9 is a diagram similar to Fig. 8 of another

2

portion of the workpiece oscillation control mechanism.

The drawing illustrates the invention as being employed in conjunction with a machine such as is shown in the Patents Nos. 2,188,223 and 2,458,708 referred to hereinabove. That is, the present invention embodies an operative mechanism which is mounted upon the basic machine as disclosed in the aforesaid patents as an accessory thereto so as to embody in the latter improved automatic control means for the purposes aforesaid. As illustrated in Figs. 1, 2, 3 for example, the basic machine includes a base or frame 10 supported by legs 12 to a convenient height; frame 10 in turn supporting the oscillating work piece carriage and the polishing or glazing rolls, and other mechanisms for driving and controlling the carriage and the rolls as will be explained hereinafter.

20 The rolls are indicated at 14—16; the roll 14 being mounted above the roll 16 and with its axis of rotation set slightly ahead of the axis of the roll 16. The roll 14 is of substantially less diameter than the roll 16, and the rolls are arranged to contact along the line of entering of the ware to be polished or glazed. The rolls 14—16 will of course be formed of any suitable material treated in any desired manner according to the character of the work to be done, and the roll 14 is carried upon a shaft 18 while the roll 16 is carried upon a shaft 19.

The shaft 18 is journaled at its opposite ends upon rocker arms 20 which extend from opposite ends of a common rocker shaft 24; the shaft 24 being in turn rotatably supported by means of pedestals 28 which extend vertically from opposite ends of the base plate 10. A second rocker shaft 30 is similarly journaled upon the pedestals 28 so as to extend parallel to the rocker shaft 24 and therebelow. Rocker arms 32 extend forwardly from opposite ends of the rocker shaft 30 in parallel relation and carry at their outer ends the lower roll shaft 19 in journaled relation thereon. The rocker shafts 24, 30 are interconnected by means of meshing gears 36, 38 which are keyed to the rocker shafts 24, 30, respectively. Adjacent the opposite ends of the rocker shafts 24, 30 they are fitted with rearwardly extending clevis arms 40, 42. The arm 40 carries a screw block 44 pivotally mounted therein, and the arm 42 carries a vertically splined stirrup 46 thereon. A hydraulic cylinder member 48 is fixed to the lower end of the stirrup 46 and slidably mounts therein a piston 50. The piston 50 is fixed upon the lower end of a screw 52 which extends upwardly through the open end of the

cylinder 48 and thence through the clevis end portion of the crank arm 42 and thence through the nut 44 which it engages in screwthreaded relation. At its upper end the screw 52 carries a hand wheel 56. A tension spring device 58 is connected at its upper end to the screw block 44 and at its lower end upon a hook device 59 which is fixed to the slide bracket 46. Thus, it will be appreciated that the spring 58 tends to bias the crank arms 40, 42 so as to open the rolls 14-16, but that the piston cylinder unit 48, 50 is operable to force the rocker cranks apart so as to bring the rolls 14, 16 together for polishing work pieces inserted therebetween. Also, it will be appreciated that the hand wheel 56 is manually adjustable for purposes of regulating the tension and distance between the rolls under operating conditions, so as to suit the machine to different classes of work. The rolls 14, 16 are arranged to be driven by any suitable means such as separate electric motors as shown and described for example in Patent No. 2,458,708.

The work mounting carriage portion of the machine is illustrated herein to comprise a table 70 which is mounted upon the base plate 10 by means of slideways 72 so that the table 70 is reciprocable horizontally in directions transverse to the rolls 14, 16. A hydraulic piston-cylinder unit 75 is mounted under the base plate 10, and the piston rod 76 thereof extends in the direction of platform travel and into connection with a bracket 77 carried by the platform 70. Thus, hydraulic actuation of the piston-cylinder unit 75 will cause the platform 70 to reciprocate toward and away from the rolls 14, 16.

A second platform 80 carrying an elevated rail 81 is mounted by means of rollers 82 (Fig. 2) which are carried by an upright extension of the platform 70 so that the platform 80 is reciprocable relative to the platform 70 in directions axially of the rolls 14, 16 independently of reciprocation of the platform 70. A hydraulic piston-cylinder unit 83 is mounted upon the platform 70, and the piston rod 84 thereof is connected at 85 to the platform 80, whereby hydraulic actuation of the piston cylinder unit 83 will cause the platform 80 to reciprocate in sidewise directions independently of backward and forward reciprocations of the platform 70.

The platform structure 80-81 includes upright 86-86 (Fig. 2) and on one end a side plate 87 which is bolted thereto by bolts 88, 88. The uprights 86, 86 mount top rails 90, 90 which extend forwardly of the brackets 86 and mount in journaled relation thereon a rocker shaft 92 which extends parallel to the rolls 14, 16. At one end of the rocker shaft 92 it carries a quadrant 94 which in turn mounts a crank pin 96. The piston rod 98 of a hydraulic cylinder-piston unit 100 is connected to the crank pin 96; the closed end of the cylinder 100 being pivotally mounted upon the bracket plate 87 as by means of a pin 101 (Fig. 3). The quadrant 94 is arcuately slotted as indicated at 102 concentrically of its mounting shaft 92, and a trip pin 104 is adjustably disposed in the slotted portion 102. A second trip pin 106 is also disposed in the groove 102 adjacent the lower end thereof, and the pins 104, 106 are positionally adjusted on the quadrant 94 so that as the quadrant oscillates in response to an operation which will be explained hereinafter, the pins 104, 106 alternately contact the actuating arm 108 of a four-way hydraulic pilot control valve 110, for actuating the latter.

The arms 90, 90 also mount short rocker shafts

112-112 (Fig. 3) and the rocker shafts 112 are connected to the cross shaft 92 by means of meshing gears 114, 116 enclosed within gear cases 117. Each rocker shaft 112 carries a bracket 118, and thus it will be appreciated that whenever the hydraulic piston cylinder unit 100 operates to reciprocate the quadrant 94, the rocker shaft and gear mechanism will operate to simultaneously cause the brackets 118-118 to rock upon the shafts 112-112.

The brackets 118-118 are grooved as indicated at 120 to receive in slide-fitting relation therein the opposite pin-shaped ends 123 of a work carrying plate 124, so that the latter may be slipped through the grooves 120 until the pin ends 123 run into the bottom ends of the grooves. Thus, a gang of spoons or forks or the like as indicated at 125 may be clamped upon the plate 124, as by means of a detachable holder bar 126, so that the work pieces are mounted to extend therefrom toward the buffing rolls. The rolls 14, 16 rotate in such direction as to at all times tend to draw the work pieces into the polishing gap.

The quadrant 94 and the brackets 118-118 and the operating mechanisms therefor are so constructed and arranged as to cause the work piece holding members to swing about the axes of the shafts 112-112, incidental to which the work pieces are caused to oscillate. Thus, it will be understood that the curved or bowl portions of the work pieces will be thereby caused to pass in and out between the rolls so as to provide progressive polishing or glazing of the curved bowl portions from the tip ends to the heel ends thereof; and that the movements of the brackets 118-118 and the pivoting of the work holder plate thereon permits the curved surfaces of the work pieces to move in intimate polishing contact with the rolls throughout all phases of displacement.

The control system for the mechanism is illustrated in Fig. 7 to include a start-stop switch 200 in series with an emergency switch 202, a counter switch 203, and the winding of a solenoid 204; in a circuit comprising conductors 205-206 connecting to any suitable power source. The emergency and counter switches are normally closed and therefore closing of switch 200 energizes the solenoid to operate a four way pneumatic valve 208 so as to permit air to flow under pressure from conduit 209 through conduit 210 and conduit 211 into the pneumatic jack 48 so as to close the rolls 14 and 16. At the same time air passing through conduit 210 enters an air-controlled hydraulic valve 212 so as to actuate the shuttle thereof to permit pressurized fluid to flow from a pump 214 through a conduit 215 and into a conduit 216 leading into the pressure supply port of a four way hydraulic valve 220. The return air lines are indicated at 221-222, and the return hydraulic lines are indicated at 223-224. A pressure relief valve is indicated at 225 for protection of the systems.

The valve 220 is of the shuttle type and is shown to include paired output ports coupled to conduits 226-227 which connect to opposite ends of the cylinder 75 to produce the in-and-out motion of the work carriage; and the valve 220 is controlled to produce reciprocation of the carriage by means of a carriage-tripped pilot valve 230 which is connected by conduits 231, 232, 233, 234 to the hydraulic pressure supply and return conduits and to the shuttle control ports of the valve 220.

As shown in Fig. 8, the control for sidewise reciprocation of the work carriage is effected by

a mechanism including a shuttle valve 235 which is similar to valve 220, and a carriage-tripped pilot valve 236 (Figs. 1-2) which is similar to valve 230; the valves 235-236 being connected to control the carriage operating cylinder 83 by means of suitable conduits as shown which correspond to the conduit connections and control arrangement referred to in Fig. 7.

As shown in Fig. 9, the control for the cylinder 100 which produces rocking of the work piece holding carriage 118 is effected by means of a hydraulic control mechanism including a shuttle valve 240 and the sector-tripped pilot valve 110 (Fig. 3) both of which are of a type similar to that of the trip valves 230-236. The valves 110-240 are connected to control the operation of the cylinder 100 by means of suitable conduits as shown which correspond to similar conduits shown in Figs. 7-8.

Thus, it will be appreciated that the control mechanism will operate upon closing of the starting switch 200 to first close the rolls 14, 16, and then to cause the carriage to reciprocate toward the rolls and transversely thereof while at the same time the work piece carrying platform 118 is caused to rock about the axis of the shaft 112, thereby effecting proper glazing or polishing of the work pieces. However, it is to be understood that the invention is not limited to the use of the three specific oscillation motions of the work pieces referred to hereinabove; and that one or more of such motions might be eliminated if not needed in the case of any given glazing or polishing problem. Upon completion of such operations the operator may, if preferred, simply actuate either the starting switch 200 or the emergency switch 202 so as to open the control circuit and thereby cause all motions to stop and the rolls to open; the control switch 200 and emergency switch 202 being preferably arranged at different positions on the machine to facilitate quick stopping of the machine whenever trouble is noted by the operator.

However, as illustrated in Fig. 7 an accessory counter switch 203 may be included in the power supply circuit; the actuator lever thereof being arranged to be reciprocated responsive to each reciprocative movement of any portion of the machine, such as for example the movement of the main carriage. Thus, the switch 203 may be of any suitable cumulative counter type such as is presently available on the market and preset so that subsequent to a preselected number of oscillations of the work carriage the switch 203 will operate to open the electrical control circuit, thereby deenergizing the solenoid 208 and stopping the entire machine operation. The addition of such a feature to the machine provides an automatic cycle control effect, and would of course eliminate the need of operator-attention to the extent of each batch-treating operation. Thus, a single operator may, for example, attend to the loading and unloading of a series of such machines, and need only start up each machine after he reloads it whereupon the latter will stop itself after a predetermined amount of work has been performed upon the work pieces.

It is a particular feature of the present invention that there is included in the machine an improved mechanism for adjustably controlling both the zone of transverse oscillation of the work piece carriage relative to the rolls and the amplitude thereof. The mechanism for accomplishing this is illustrated in Figs. 1, 2, 5, 6 to include a pair of bearing blocks 250-250 which are slid-

ably mounted upon the transverse rail 80 for free sliding movements therealong and interconnected by means of a screwthreaded control rod 252 which is oppositely threaded (that is, right hand and left hand) in the zones of screwthreaded connection thereof with the oppositely disposed bearing blocks 250-250. The rod 252 carries a manual control wheel 254, whereby it will be appreciated that rotation of the wheel 254 will cause the bearing blocks 250-250 to move either toward or away from each other. Blocks 250-250 carry as integral parts thereof finger devices 255-255 which are arranged to engage the actuating lever arm 256 of the pilot valve 236 upon transverse reciprocation of the work piece carriage. Thus, it will be appreciated that manual manipulation of the hand wheel 254 will adjust the amplitude of the transverse stroke of the work piece carriage.

20 The rod 252 also carries a collar 258 which positions thereon a bracket 259 which is engaged through means of a screwthread connection with a second control rod 260 having its head end portion extending to a position within convenient reach of the operator and terminating in a hand wheel 262. The bracket 259 is engaged upon the collar 258 so that the rod 252 is freely rotatable therein; and thus it will be appreciated that manual adjustments of the hand wheel 262 will 25 result in positive displacements of the control rod 252 in directions parallel to the axes of the rolls 14-16. Thus, the position of the zone of transverse carriage movement relative to the rolls may be laterally shifted at will, independently of adjustments of the amplitude or length of strokes thereof. This feature of the invention facilitates adaptation of the machine to different work piece mountings and to glazing or polishing of variously shaped work pieces, and permits adjustment of the machine to compensate for variable wear of the roll devices and to suit the machine to operate upon widely different articles.

It is another feature of the present invention that a novel operation "dwell" control arrangement is provided to facilitate any desired slowing down or speeding up of any phase of a reciprocating cycle of the work pieces relative to the rolls 14, 16, whereby the glazing or polishing operation may be emphasized or minimized on different portions of the work pieces, such as may be particularly desirable on work pieces of irregular shapes such as spoons, forks, or the like. For this purpose, by way of one example thereof, Figs. 1-2 and 4 illustrate connection to one end 45 of the shaft 92 of a cam 270 which is arranged to track against a roller finger portion 272 of a throttle valve device 274 which is connected into one of the hydraulic lines leading to the cylinder 100 controlling oscillation of the work carrying platform (Fig. 9). The valve 274 may 50 be of any suitable type for variably throttling the flow of hydraulic fluid therethrough as controlled by the finger 272, and preferably is provided with a manual adjustment device 275 whereby the operator may adjust the range of fluid flow through the valve independently of operation thereof as 55 provided by the control finger 272.

As shown in Fig. 4, the cam 270 is shaped so 70 that as the shaft 92 rocks incidental to operations of the cylinder 100 as explained hereinabove, the cam 270 is thereby caused to variably press against the valve stem 272 so as to provide the desired degree of slowing down of the rocking movement of the platform 118 at the desired 75 phase of its cycle of rocking. Thus, the device

is readily adjustable to either emphasize or minimize the amount of glazing or polishing action applied to different areas of the work pieces carried by the frame 118.

Thus, it will be appreciated that the machine of the present invention embodies novel and important operational control and adjustment features which adapt the machine to more nearly fully automatic and otherwise improved modes of operation, especially when operating upon work pieces of irregular shapes. Also, it will of course be appreciated that although only one form of the machine of the invention has been illustrated and described in detail herein, it will be apparent to those skilled in the art that the invention is not so limited but that various changes may be made therein without departing from the spirit of the invention or the scope of the appended claims.

What is claimed is:

1. In a polishing and glazing machine, in combination, a pair of rolls, a slide member movable towards and away from the rolls in a line at right angles to the longitudinal axes of the rolls, a platform carried by said slide member and movable thereon in directions parallel to said rolls, a work holder carried by said platform by means of pivotal connections therewith having pivot axes parallel to said rolls, means for causing said slide member and said platform to independently oscillate, and drive means to cause the work holder to pivot relative to said platform, said work holder being constructed and arranged so as to support a plurality of work pieces to extend forwardly therefrom for passage between said rolls for polishing or glazing purposes, power supply means coupled to said slide member and to said platform and to said work holder for oscillation thereof, and said drive means being controlled by a variably controllable power throttling device in turn controlled by movement of said work holder to vary the speed of pivoting of said holder at different phases of its movements about said pivotal connections thereof.

2. In a polishing and glazing machine, a pair of rolls, a platform carried by said machine and oscillatable thereon, a work holder carried by said platform for oscillation relative thereto, said work holder being constructed and arranged so as to support a plurality of work pieces to extend forwardly therefrom for passage between said rolls for polishing or glazing purposes, hydraulic actuating means including a hydraulic fluid pressure supply and conduit means operable to oscillate said work holder relative to said rolls, a throttle valve controlling the rate of fluid flow through said conduit means, and cam means geared to said work holder for movement therewith and operable to control said throttle valve for varying the rate of said work holder movement during different phases of oscillation thereof.

3. In a polishing and glazing machine for surface finishing batches of work pieces, a pair of parallel rolls, a work holder adapted to mount a plurality of work pieces to be extended toward the gap between said rolls, said holder being carried by said machine by means of connections therewith whereby said work holder is displaceable to reciprocate the work pieces in the polishing gap between the rolls, hydraulic jack means operable to move said work holder relative to said rolls, and a hydraulic jack control means including a pressurized fluid supply conduit system controlled by a reversing direction pilot valve actu-

ated by said work holder upon movements thereof in opposite directions, said work holder having positionally adjustable paired abutment devices thereon operable to contact and actuate said pilot valve to thereby determine the limits of the reciprocation strokes of said work holder, and manual control means carried by said holder and operable to selectively shift the positions of said abutment devices relative to said work holder for variations of the range of stroke of said holder and the position of said stroke range relative to said rolls.

4. In a polishing and glazing machine, in combination, a roll, a slide member movable towards and away from said roll in a line at right angles to the longitudinal axes of said roll, a platform carried by said slide member and movable thereon in directions parallel to said roll, a work holder carried by said platform by means of pivotal connections therewith having pivot axes parallel to said roll, means for causing said slide member and said platform to independently oscillate, and hydraulic jack means to cause the work holder to pivot relative to said platform, said work holder being constructed and arranged so as to support a plurality of work pieces to extend forwardly therefrom for passage against said roll for polishing or glazing purposes, power supply means coupled to said slide member and to said platform and to said work holder for oscillation thereof, said hydraulic jack means being controlled by a throttle valve in turn controlled by movement of said work holder to vary the speed of pivoting of said holder at different phases of its movements about said pivotal connections thereof, and counter means actuated upon movement of said work holder to count the oscillations thereof and operable upon accumulation of a predetermined number of oscillation counts to disconnect said power supply means to stop said machine.

5. In a polishing and glazing machine, in combination, a pair of rolls, roll control means to open and close said rolls relative to one another, a slide member movable towards and away from the rolls in a line at right angles to the longitudinal axes of the rolls, a platform carried by said slide member and movable thereon in directions parallel to said rolls, a work holder carried by said platform by means of pivotal connections therewith having pivot axes parallel to said rolls, means for causing said slide member and said platform to independently oscillate, and means to cause the work holder to pivot relative to said platform, said work holder being constructed and arranged so as to support a plurality of work pieces to extend forwardly therefrom for passage between said rolls for polishing or glazing purposes, power supply means coupled to said roll control means and to said slide member and to said platform and to said work holder for oscillation thereof, speed control means including speed pattern means responsive to movement of said work holder and adapted to establish a definite correlation between the position of said work holder in its pivotal cycle of oscillation and the speed of pivoting of said work holder according to an arbitrary predetermined pattern, whereby said pivoting may be automatically retarded at any desired predetermined portion of said cycle of oscillation, and counter means actuated upon movement of said work holder to count the oscillations thereof and operable upon accumulation of a predetermined number of oscillation counts

to disconnect said power supply means to stop said machine and to open said rolls.

6. In a polishing and glazing machine, a pair of rolls, a work holder constructed and arranged so as to support a plurality of work pieces to extend forwardly therefrom for passage between said rolls for polishing or glazing purposes, a hydraulic actuating means for oscillating said work holder relative to said rolls, a hydraulic fluid pressure supply and conduit means operatively connected to said hydraulic actuating means, a throttle valve controlling the rate of fluid flow through said conduit means, and cam means geared to said work holder for movement therewith and operable to control said throttle valve for varying the rate of said work holder movement during different phases of oscillation thereof.

7. In a polishing and glazing machine for surface finishing batches of work pieces, a roll, a work holder adapted to mount a plurality of work pieces to be extended toward said roll, said holder being carried by said machine by means of connections therewith whereby said work holder is displaceable to reciprocate the work pieces against the roll, hydraulic jack means operable to move said work holder relative to said roll, and a hydraulic jack control means including a pressured fluid supply conduit system controlled by a reversing direction pilot valve actuated by said work holder upon movements thereof in opposite directions, said work holder having positionally adjustable paired abutment devices thereon operable to contact and actuate said pilot valve to thereby determine the limits of the reciprocation strokes of said work holder, and manual control means carried by said holder and operable to selectively shift the positions of said abutment devices relative to said work holder for variations of the range of stroke of said holder and the position of said stroke range relative to said roll.

8. In a polishing and glazing machine, in combination, a pair of rolls, roll control means to open and close said rolls relative to one another, a slide member movable towards and away from the rolls in a line at right angles to the longitudinal axes of the rolls, a hydraulic actuator including fluid pressure supply and conduit means operable to oscillate said slide member relative to said rolls, a throttle valve controlling the rate of fluid flow through said conduit means, and cam means geared to said slide member for move-

ment therewith and operable to control said throttle valve for varying the rate of said slide member movement during different phases of oscillation thereof, a platform carried by said slide member and movable thereon in directions parallel to said rolls, hydraulic jack means operable to move said platform relative to said rolls, and a hydraulic jack control means including a pressured fluid supply conduit system controlled by a reversing direction pilot valve actuated by said platform upon movements thereof in opposite directions, said platform having positionally adjustable paired abutment devices thereon operable to contact and actuate said pilot valve to thereby determine the limits of the reciprocation strokes of said platform, and manual control means carried by said platform and operable to selectively shift the positions of said abutment devices relative to said platform for variations of the range of stroke of said platform and the position of said stroke range relative to said rolls, a work holder carried by said platform by means of pivotal connections therewith having pivot axes parallel to said rolls, means for causing said slide member and said platform to independently oscillate, and means to cause the work holder to pivot relative to said platform, said work holder being constructed and arranged so as to support a plurality of work pieces to extend forwardly therefrom for passage between said rolls for polishing or glazing purposes, power supply means coupled to said roll control means and to said slide member and to said platform and to said work holder for oscillation thereof, and counter means actuated upon movement of said work holder to count the oscillations thereof and operable upon accumulation of a predetermined number of oscillation counts to disconnect said power supply means to stop said machine and to open 40 said rolls.
